UNITED STATES PATENT OFFICE.

EARLE BUCKINGHAM, OF HARTFORD, CONNECTICUT, ASSIGNOR TO PRATT & WHITNEY COMPANY, OF NEW YORK, N. Y., A CORPORATION OF NEW JERSEY.

LOST-MOTION-COMPENSATING MEANS FOR GEAR-HOBBLING MACHINES.

Application filed October 12, 1922. Serial No. 594,150.

To all whom it may concern:

Be it known that I, EARLE BUCKINGHAM, a citizen of the United States, residing at Hartford, in the county of Hartford and 5 State of Connecticut, have invented certain new and useful Improvements in Lost-Motion-Compensating Means for Gear-Hobbing Machines, of which the following is a specification.

10 This invention relates to gear hobbing machines and in particular to mechanism for machines of this type whereby all lost motion in the gear train between the hob and work spindle is eliminated.

15 It is an object of the invention to provide simple and inexpensive mechanism which will eliminate all inaccuracies in the hobbing operation due to lost motion or back 20 lash between parts of the machine and which will not place a drag on the work spindle.

One feature which enables me to accomplish the above named object is that I provide two driving connections from the hob spindle to the work supporting and rotating 25 spindle, one of these connections being a positive gear connection throughout and the other connection being a frictional one preferably comprising a train of gears provided with a frictional clutch interposed 30 therein. This frictional driving connection is adapted to be driven as by a differential gear at a slightly increased speed. By this means the timing of the work spindle is controlled entirely by the positive geared 35 connections and the frictionally driven connections tend to force the work spindle as far in advance as possible, thus holding all of the lost motion or back lash of the parts in the positive driving connections on the 40 same side of the gear teeth.

Particularly, it is an object of the present invention to provide substitute means for the form of lost motion compensating means described and claimed in my copending application Serial No. 593,309 filed October 9, 45 1922.

With this and other objects in view, my invention consists in the features of operation set forth in the following specification 50 and illustrated in the accompanying drawing.

In the accompanying drawing annexed hereto and forming a part of this specification, I show in diagrammatic form a view 55 of the cooperative mechanism of a hobbing

machine which is provided with the present invention. It will be understood, however, that the invention can be otherwise embodied and that the drawing is not to be construed as defining or limiting the scope 60 of the invention, the claims appended to this specification being relied upon for that purpose.

In the drawing:

Figure 1 is a diagrammatic view in plan 65 of the mechanism forming the present invention, and

Fig. 2 is a front elevation of the mechanism also shown diagrammatically.

In the above mentioned drawing, I have 70 shown but one modification of the invention which is now deemed preferable but it is to be understood that changes and modifications may be made within the scope of the 75 appended claims without departing from the spirit of the invention.

Briefly, my invention in its broadest aspect comprises the following principal parts: first, a hob supporting and rotating spindle 80 preferably provided with suitable driving means directly attached in alignment therewith; second, a work spindle adapted to rotate the work in timed relation to the rotation of the hob spindle and adapted simultaneously to advance the work axially past the hob; third, a positive driving connection between the hob spindle and the work supporting and rotating spindle composed throughout of toothed gearing; fourth, another set of gearing including a differential 85 gear to increase the speed ratio of this second geared connection; fifth, a friction clutch incorporated in the second driving connection; sixth, elongated pinions forming the final 90 elements of both of the driving connections and adapted to directly engage the indexing gear fastened directly to and moving axially with the work spindle.

Referring more in detail to the figures of the drawing, at 10 is shown a hob spindle 100 having a hob 11 of suitable form thereon. This hob spindle 10 is adapted to be rotated in bearings provided in the base or other part of the machine shown diagrammatically at 12. Disposed at right angles to the axis 105 of the hob spindle is a work spindle 14 which also may be suitably supported in the base or other part of the machine so that it may be rotated and simultaneously advanced axially. In the preferred embodiment 110

ment of the invention the axes of both the hob and work spindle are fixed in predetermined angular relation. On this spindle 14 I provide an indexing gear 15. Directly attached to the spindle 14 by any suitable fastening means, I mount gear blanks W which are adapted to be cut by the hob, these being mounted coaxially with the spindle in the usual way. In alignment with the work 5 spindle 14 is a screw 16 engaging a threaded member 17 attached to or forming a part of the base of the machine. It will be seen from this construction that as the work spindle 14 is rotated, it will be simultaneously advanced in an axial direction by the engagement of the screw 16 within nut 17.

In order to rotate the work spindle 14 in timed relation to the rotation of the hob spindle 10, I provide a positive geared 10 driving connection between these two spindles. Preferably, a bevel gear 20 fast to the hob spindle is in mesh with another bevel gear 21 on a short intermediate shaft having a pinion or gear 22. In mesh with the 15 gear 22 is an idler gear 23 which in turn engages another gear 24. Preferably the gears 22 and 24 are arranged so that they may be conveniently removed and the idler so adjustably positioned that it may engage 20 both of them. The gear 24 is fixed to and drives a shaft 25 having an elongated pinion 26. This pinion 26 is adapted to engage directly with the teeth of the indexing gear 15 in all axial positions of the work spindle 25 14 and gear 15.

A second driving connection is provided 30 between the hob spindle 10 and work spindle 14 which may also be driven by the bevel gear 20 on the hob spindle 10. This driving connection comprises a bevel gear 30 on a shaft having a gear 31 thereon which is in mesh with an intermediate gear 32. The gear 32 is in mesh with one of the gears 33 of a pair of gears 33 and 34, these two 35 gears being of slightly different diameter and fastened together so that they are positively rotated simultaneously. In mesh with the gear 34 of this pair is gear 35 on a shaft 36 to which is splined or otherwise 40 fastened one set of disk members of the friction clutch 37. The other set of members and also the housing of this friction clutch 37 are fastened to or integral with an elongated pinion 38 loosely surrounding the 45 shaft 36. Springs 39 housed within a closing member 40 of the friction clutch 37 provide means for regulating the friction within the clutch. The elongated pinion 38 driven by the clutch 37 is directly in mesh 50 with the teeth of gear 15 throughout the axial movement of the spindle 14 and gear 15.

It will be seen from the above construction that the timed relation between the rotation of the hob spindle 10 and the work 55 spindle 14 is governed entirely by the posi-

tive driving means including the gears 21 to 26 and that this ratio may be varied within wide limits by substituting for gears 22 and 24 other gears of different numbers of teeth. The driving connection provided between the gears 30 to 35 by reason of the interposition of the differential gear 34—35 rotates the shaft 36 at a slightly higher speed than the shaft 25 so that the tendency of this shaft 36 through the friction clutch 37 and the pinion 38 attached thereto is to drive the gear 15 at a slightly faster rate than called for by the positively driven pinion 26. The positive connections however prevent this and cause the friction clutch 37 to slip slightly. The gear 15 however is held as far advanced as permitted by the positively driven pinion 26 by reason of the increased speed of the shaft 36. Thus all lost motion or back lash between the members of the positive driving train including gears 21 to 26 is continuously held upon the same side of the teeth and any lost motion between these members does not in any way affect the precision of the mechanism. 90

What I claim is:

1. A gear hobbing machine having cooperating mechanism comprising, a work supporting and rotating spindle, a rotatable hob supporting means, a hob thereon, driving means for said hob and spindle, two driving connections between said hob and spindle, and means to axially advance the work spindle during operation. 95

2. A gear hobbing machine having cooperating mechanism comprising, a work supporting and rotating spindle, a rotatable hob supporting means, a hob thereon, driving means for said hob and spindle, two driving connections between said hob and spindle, elongated pinions on said driving connections, and a gear on said work spindle adapted to mesh with said pinions during operation of the machine. 100

3. A gear hobbing machine having cooperating mechanism comprising, a work supporting and rotating spindle, a rotatable hob supporting means, a hob thereon, driving means for said hob and spindle, and positive and frictional driving connections between said hob and spindle. 110

4. A gear hobbing machine having cooperating mechanism comprising, a work supporting and rotating spindle, a rotatable hob supporting means, a hob thereon, driving means for said hob and spindle, positive and frictional driving connections between said hob and spindle, and means to axially advance the work spindle during operation. 120

5. A gear hobbing machine having cooperating mechanism comprising, a work supporting and rotating spindle, a rotatable hob supporting means, a hob thereon, driving means for said hob and spindle, positive and frictional driving connections between said 125

hob and spindle, elongated pinions on said positive and frictional driving connections, and a gear on said work spindle adapted to mesh with said pinions during operation of the machine.

6. A gear hobbing machine having cooperating mechanism comprising, a work supporting and rotating spindle, a rotatable hob supporting means, a hob thereon, driving means for said hob and spindle, two driving connections between said hob and spindle, the ratio of said driving connections being slightly different, and a friction clutch included in one of said driving connections.

15 7. A gear hobbing machine having cooperating mechanism comprising, a work supporting and rotating spindle, a rotatable hob supporting means, a hob thereon, driving means for said hob and spindle, two driving connections between said hob and spindle, the ratio of said driving connections being slightly different, and a friction clutch included in the faster running driving connection.

25 8. A gear hobbing machine having cooperating mechanism comprising, a work supporting and rotating spindle, a rotatable hob supporting means, a hob thereon, driving means for said hob and spindle, two driving connections between said hob and spindle, the ratio of said driving connections being slightly different, a friction clutch included in one of said driving connections, and elongated pinions on said driving connections, 35 and a gear on said work spindle adapted to mesh with said pinions during operation of the machine.

9. A gear hobbing machine having coop-

erating mechanism comprising, a work supporting and rotating spindle, a rotatable hob supporting means, a hob thereon, driving means for said hob disposed in alignment therewith, and two driving connections from said driving means for said hob to said spindle whereby said hob and spindle may be rotated in timed relation to each other, one of said connections being positive and the other connection being frictional.

10. A gear hobbing machine having cooperating mechanism comprising, a work supporting and rotating spindle, a rotatable hob supporting means, a hob thereon, driving means for said hob disposed in alignment therewith, and two driving connections from said driving means for said hob to said spindle whereby said hob and spindle may be rotated in timed relation to each other, one of said connections being positive and the other connection being frictional, the frictional connection being adapted to rotate faster than said positively driven connection.

11. A gear hobbing machine having cooperating mechanism comprising, a work supporting and rotating spindle, a rotatable hob supporting means, a hob thereon, driving means for said hob disposed in alignment therewith, and two driving connections from said driving means for said hob to said spindle whereby said hob and spindle may be rotated in timed relation to each other, one of said connections being geared throughout and the other connection including a friction clutch.

In testimony whereof, I hereto affix my signature.

EARLE BUCKINGHAM.
